FIG. 5.

UNITED STATES PATENT OFFICE.

CARL SPRINGFELS, OF BUFFALO, NEW YORK.

BOX.

1,250,689.

Specification of Letters Patent. Patented Dec. 18, 1917.

Application filed September 8, 1916. Serial No. 119,003.

To all whom it may concern:

Be it known that I, CARL SPRINGFELS, a citizen of the United States, residing at Buffalo, in the county of Erie and State of New York, have invented certain new and useful Improvements in Boxes, of which the following is a specification.

My invention relates to the class of boxes having a hinged cover, or lid, and which is provided with a spring serving to hold the same in either a closed or open position.

The object of my invention is to provide a new and improved spring for spring lid boxes and especially jewelry boxes, and means to fasten same to the box and lid after they are covered.

This class of box is usually covered with plush, velvet or leather and then suitable backs or cushions inserted. By use of my improved spring and fastening, the box and lid may be covered separately by machinery and afterward fastened together.

In the accompanying drawings, illustrating the preferred form of my invention, Figure 1 is a view in perspective of a box embodying my invention. Fig. 2, is a sectional elevation of the closed box on a line C—C of Fig. 3. Fig. 3, is a sectional elevation of the closed box and showing the hinge and spring. Fig. 4, is a side view of the spring and showing it in dotted lines in different positions. Fig. 5, is a sectional elevation of the open box on the line C—C of Fig. 3. Fig. 6, is a dotted front elevation of the spring shown in detail in Fig. 4. Fig. 7 is a sectional view of the box on line B—B of Figs. 3 and 5, showing the hinge and method of fastening to the box. Fig. 8, is a side view of the hinge and showing it in dotted lines in different positions.

Having reference to the drawings, there is shown a box commonly employed for holding jewelry. It comprises a lower part or box 2, and an upper part or lid 1, which are preferably constructed of light stamped sheet metal as 4 and 3, but may equally well be constructed of other suitable material. 5 and 6 represent a covering of plush or other similar or suitable material. 7 represents the hinge (see Fig. 8) on which are formed small lips or projections 8, 8, for retaining the spring 12 by means of the slots 16, 16. 9, 9, 9, and 9 (Fig. 3) represent slots in the hinge 7, and 15, 15 (Fig. 7) similar slots in the box 2 for inserting the locking strips 11, 11 to fasten the hinge 7 to

the box 2 and lid 1. 10, 10, 10 and 10 are the ends of strips 11, 11 which are bent over to retain the strips 11, 11 in position as shown. No invention is claimed for the 60 method of attaching the hinge 7 to the members of the box by means of the locking strips 11, 11, as the hinge may be attached to the members by any one of various methods such as rivets, solder, etc. 65

The spring 12 is normally of the shape shown in Fig. 4 and having a substantial right angle X to hold the lid 1 in an open position as shown in Fig. 5, and 13 and 14 represent different positions of the spring 70 12 when the lid 1 of the box 2 is in a half closed and in a closed position. The hinge 7 is shown in Fig. 8 in the same position as in Fig. 5 where the lid is open and 17 and 18 represent different positions of the hinge 75 7 when the lid 1 of the box 2 is in a half closed and in a closed position.

The spring 12 and hinge 7 are shown engaged in Fig. 5 as they are when mounted in a box, with the lid open, and with the lid 80 closed in Figs. 2 and 3.

In my construction the locking strips 11, 11 are first inserted in the slots 15, 15 of the lid 1 and box 2, then the coverings 5 and 6 of the lid 1 and box 2 are put on and then 85 the hinge 7 is fastened in place on the lid and box by inserting the locking strips 11 and 11, and bending over the ends 10, 10, 10 and 10. The spring 12 is then put in place by inserting one of the lips 8 on the hinge 7 through one of the slots 16 in the spring 12 and half closing the lid 1 so the hinge 7 is in the position shown by dotted lines 17 (Fig. 8). The spring 12 is then straightened out until the ends are separated sufficiently for the other lip to be 95 inserted in the remaining slot 11.

The spring 12 is normally at rest as shown in Fig. 5 and holds the lid 1 of the box 2 open but is not exerting any pressure on the hinge 7 except as the lid 1 may be moved. When the lid 1 is moved from the full open toward a closed position, the spring 12 exerts a pressure against this movement as the lower end of the spring is 100 substantially pivoted while the upper end is moved and the spring straightened out until the lid is practically half closed and the spring and hinge are in the positions 13 and 17 as shown in Figs. 4 and 8. The 110 hinge 7 is now opened on practically a straight line A—A and the spring 4 is

straightened so its ends are separated to the limit for the operation of the hinge. Continuing to close the lid the spring 12 now assists in the movement as its ends are moving toward each other to more nearly assume its normal position. The reason of this is that the hinge 7 is farthest open in position of line A—A and is partially closing from position 17 to position 18. When 10 the lid 1 is closed, the spring 12 exerts a pressure to hold it in that position as the spring is somewhat straightened from its normal right angle position, as shown in Fig. 2.

15 I have thus described a way of constructing and using my invention, without attempting to set forth all the forms in which it may be made or all the modes of its use. Accordingly the claims are to be interpreted as contemplating such variations 20 in form and manner of use.

Copies of this patent may be obtained for five cents each, by addressing the "Commissioner of Patents, Washington, D. C."

What I claim is:

The combination with a box and lid; of a hinge distinct therefrom having each of its leaves provided with a centrally located 25 projection at its edge and a detachable flat spring having two oppositely arranged recesses located centrally at the edges of said spring in which said projections are respectively positioned before said hinge is 30 fastened in place, whereby said lid may be yieldingly held in either an open or a closed position.

In testimony whereof, I have signed my name to this specification in the presence of 35 two subscribing witnesses.

CARL SPRINGFELS.
